UNITED STATES PATENT OFFICE.

HARRIET McELDONNEY, OF WINDSOR, ONTARIO, CANADA.

CHILD'S APPAREL-SUPPORTER.

1,351,579.

Specification of Letters Patent. Patented Aug. 31, 1920.

Application filed September 14, 1918. Serial No. 254,060.

To all whom it may concern:

Be it known that I, HARRIET McELDONNEY, a subject of the King of Great Britain, residing at Windsor, in the county of Essex,

5 Province of Ontario, Dominion of Canada, have invented certain new and useful Improvements in Children's Apparel-Supporters, of which the following is a specification, reference being had therein to the accompanying drawings.

This invention relates to an apparel supporter particularly adapted for children's wear and its object is to provide means whereby the weight or strain of supporting 15 stockings, skirts, trousers and other garments, is brought upon and carried over the shoulders of the wearer.

A further object of the invention is to provide a simple and convenient apparel 20 support adapted to hang freely from the shoulders of the wearer and swing free of the garment at its lower end to which it is attached at that portion extending over the shoulders. It is also an object of the invention 25 to provide a simple, cheap and efficient construction having certain other new and useful features, all as hereinafter more fully described and particularly pointed out in the appended claims, reference being had 30 to the accompanying drawings, in which

Figure 1 is a plan view of a garment embodying the invention showing the same in extended position, and with portions broken away to show the construction;

35 Fig. 2 is a similar view illustrating a slightly modified construction;

Fig. 3 is a similar view showing a further modified construction; and

40 Fig. 4 is an illustration of the construction shown in Fig. 1 showing the same in use.

To support the trousers, skirts and other garments and also form a support and place of attachment for the hose supporters of 45 children's wearing apparel, an underwaist is usually employed which is provided with buttons or other means along the waist line for the attachment of the trousers and other garments thereto and also for the attachment 50 of hose supporters, but the weight and strain put upon such an underwaist causes it to pull across a child's back and is therefore injurious as well as being uncomfortable to wear. The objectionable features of 55 such a garment are overcome in the construction embodying this invention and

while in Figs. 1 and 4, I have shown the usual form of underwaist provided with means embodying the invention, it will be understood that any suitable form of underwaist may be employed or the construction thereof varied as desired without departing from the spirit of the invention.

In Figs. 1 and 4 an underwaist of an old and well known form is shown having a 60 body portion 1 provided with reinforcing strips or tapes 2 which together serve as a belt which encircles the body of the wearer and to which may be attached buttons 3 for supporting garments at the middle of the 65 front. The waist is also provided with the usual button and button hole strips 4 for uniting the garment at the back and this waist is usually made sleeveless being provided with arm holes 5 forming strap portions 6 extending over the shoulders.

To form a support for outer garments such as trousers, and skirts and also a place of attachment for the usual hose supporters 7, shown in Fig. 4, a hanger or yoke member 8 is provided to encircle each arm hole of the garment and is applied to the outer side thereof, being attached thereto by lines of stitching 9 securing the hanger to the waist along the shoulder portion thereof, 80 the lower portion of the hanger being left free of the waist so that it may swing independently thereof and conform to the movements of the child's body and the changes 85 in the direction of strain put thereon. This 90 hanger is preferably made of the same material as the waist, such as cotton cloth and is of oval shape with a center opening 9 95 preferably of greater diameter than the arm hole of the waist. The narrowed or tapering lower portion of the hanger extends downwardly and overlaps the waist band of the garment and if desired this portion may be reinforced by suitable strips or tapes 10 secured there across in substantial alinement 100 with the tapes 2 on the waist. Buttons 11 may be secured to the tapes 10 for the attachment of garments and holes 12 are provided at the lower end of each hanger to receive a safety pin 13 of the supporter 7. 105 The hangers may be further reinforced about the holes 12 by securing a strip or tape 14 across the lower end of the hanger parallel with the tapes 10.

The stitching 9 which secures each hanger 110 to the waist, extends over the shoulder and downward at each side of the armhole for

only a portion of the length of each side of the arm hole, but if desired each hanger may be further secured to the waist by a line of stitching 15 extending along the front edge 5 of each hanger downwardly for a short distance from the end of the stitching 9 to prevent the hangers from swinging too freely relative to the waist and more firmly secure them in place against being torn loose under strains.

10 The greatest strain or pull is exerted by the hose supporters and this strain is taken directly by the hangers and transmitted to the shoulders of the child without putting 15 a strain upon the waist which would tend to draw it closely about the body of the wearer and transfer this weight or pull to the child's waist and back. The weight or strain of the outer garments such as trousers or skirts is also mainly taken by these loop members or hangers and transferred to the child's shoulders where it will cause no inconvenience or injury.

15 The waist 1 therefore simply forms a 25 means for connecting the two hanger members and for holding these members in place upon the child's shoulders, therefore the form or construction of the waist or means for holding the hangers in place may 30 be varied as desired, a suitable construction thereof for summer wear being shown in Fig. 3 in which the waist or body portion is formed entirely of strips or straps, there being a curved strap 16 connecting the 35 upper portions of the hangers 17 at the middle or front part of the garment with short curved straps 18 connecting the rear sides of the upper portion of the members 17 with the upper ends of the button and button 40 hole strips 19 at the back of the garment. Other straps 20 connect the strips 19 with the rear sides of the hangers 17 midway of the length of said hangers and the strap 21 connects the forward side of these 45 hangers across the front of the garment. If found desirable a waist band 22 may also be provided extending parallel with the strips 20 and 21 and connected at its ends to the button and button hole strips 19. 50 When the garment is provided with the waist band 22, the strips 20 and 21 may be dispensed with if so desired and the hangers 17 made fast to the waist band. The strips 16 and 21, and band 22 are preferably 55 connected by a cross band or strip 23 at the center of the front of the garment for the attachment of buttons 24 for supporting outer garments.

60 In the constructions illustrated in Figs. 2 and 3, the portions of the hanger members and of the body or waist which extend over the shoulder, are dispensed with and a single yielding strip 25 such as elastic webbing substituted therefor, the ends of 65 the webbing being firmly secured by stitch-

ing to the supporting members 17 and the body or waist.

In the several constructions the oval shaped yokes or supporting members hang 70 from the shoulders and are free to swing at their lower ends so that the strain of supporting garments comes at all times directly upon the shoulders where it cannot harm the child and will cause no inconvenience or discomfort. Obviously, the particular shape, form or construction of these yokes or hangers may be varied as desired without departing from the spirit of the invention, they being formed from fabric or any other suitable material and made up 80 of one or more pieces as found desirable.

75 What I claim is:—

1. An apparel support comprising a body having arm holes and adapted to be secured about the wearer, annular oval-shaped supporting members each having an arm hole of greater dimensions than the arm holes of the body, said members being secured to the body throughout the portions thereof which extend over the shoulders of the wearer 90 and downwardly to points midway of the arm holes in the body, said portions of said members which are secured to the body being positioned at a distance from the upper portion of the arm holes of the body to rest 95 well upon the shoulders of the wearer and the unsecured portions of said members being free below the lower portions of the body arm holes to swing independently of the body, and means on the lower end portions of said members beneath the arm holes for the attachment of garments thereto.

100 2. An apparel support comprising a body having arm holes and adapted to be secured about the wearer, annular oval-shaped supporting members each having a central opening of greater dimensions than the dimensions of the arm holes in the body, said members comprising a single thickness of material secured along the edges of the upper portion thereof to the body over the shoulder of the body, the edge of the opening in each of said members being spaced from the edge of the arm hole of the body to rest upon the shoulder portion of the 115 body at a distance from the upper part of the arm hole thereof, said stitching for securing said members to said body extending downwardly along the edges of said members at the rear side of said arm holes 120 to points substantially midway of the vertical length of said arm holes and at the forward side of said arm holes to points substantially in the horizontal plane of the lower ends of the arm holes, said members being free of the body from the lower ends of the stitching, and means on the lower ends of said members vertically beneath the arm holes for the attachment of garments thereto.

3. An apparel support comprising two supporting members each forming an opening through which an arm of the wearer is inserted with a portion extending over and supported by the shoulder of the wearer and a portion extending downwardly to the waist line vertically beneath an arm hole for the attachment of garments thereto, said supporting members each including a yieldable portion at the upper end thereof, and

means connecting at front and back the upper portions only of said supporting members which extend over the shoulders for holding said members in place.

In testimony whereof I affix my signature 15
in the presence of two witnesses.

HARRIET McELDONNEY.
